SEALING TOOL

John R. Proctor, Bayonne, N. J., assignor to Atlas Steel Barrel Corporation, Bayonne, N. J., a corporation of New Jersey

Original application August 30, 1938, Serial No. 227,601. Divided and this application April 9, 1942, Serial No. 438,344

11 Claims. (Cl. 113—18)

This application is a division of my copending application Serial No. 227,601, filed August 30, 1938, now Patent 2,282,495.

The invention relates to sealing metal containers against unauthorized opening and has particular reference to a means for sealing the plugged bung flange of metal drums in such manner as to preclude undetected removal of the plug to permit access to the contents of the drum.

The invention pertains especially to effectively sealing the plug against undetected access by means of a simple, inexpensive seal-cap so constructed and arranged that it may be rapidly positioned in the flange without need of laborious centering, and subsequently locked in place by means of my improved tool rapidly and with a minimum of effort on the part of the worker.

An important feature of the invention resides in the ease with which the seal-cap may be applied and the simplicity of the operation by which it is locked in place. In accordance with the present invention the seal-cap is simply dropped in a recess provided therefor in the outer surface of the bung flange. The cap is provided with a peripheral flange which may then be expanded or forced radially outwardly with the aid of my improved tool into an undercut portion or cleft extending around the periphery of this recess, thereby locking the cap in its seat.

Other important features of the invention reside in the particular construction and arrangement of parts whereby the above objects are attained, the simplicity and ruggedness of my improved mechanism for accomplishing the same, and the effectiveness of the joinder between seal-cap and flange which is obtained through the use of my tool.

Various other objects and meritorious features of the invention will be apparent from the following description taken in conjunction with the drawings, wherein like numerals refer to like parts throughout the several figures, and wherein:

Figure 1 is an elevation of my improved tool for performing the sealing operation;

Fig. 2 is a fragmentary elevation, partly in section, illustrating the position of the tool after expanding the seal-cap into locking engagement with the bung flange;

Fig. 3 is a section along 3—3 of Fig. 2;

Fig. 4 is a section illustrating the initial step in operatively positioning the seal-cap in the bung flange;

Fig. 5 is a section similar to Fig. 4 with the seal-cap expanded into locking engagement with the bung flange, and

Fig. 6 illustrates in section a detail of the tool.

Referring now to Fig. 2 of the drawings, the reference numeral 10 represents the metal stock of a drum provided with an aperture adapted to receive a bung assembly. A bung ring having a flange 12 and internally threaded to receive plug 14 is positioned within the aperture in any suitable manner. As here shown the shank of the bung is extruded or expanded radially outwardly as indicated at 14 to grip the metal of the barrel stock immediately surrounding the aperture, together with backing ring 16, firmly between the extruded portion and the flange. Rotation of the bung ring within the aperture 15 may be prevented by any suitable means, here shown in the form of biting surfaces 18 around the exterior of the bung ring shank immediately below the flange which are expanded into biting engagement with the side wall of the aperture 20 and with the side wall of the backing ring 16.

The upper surface of flange 12 is provided with a recess 20 having an undercut or cleft 22 extending around its periphery. While the angle of undercut is not of paramount importance, I have determined that 45° is satisfactory.

One form of seal-cap suitable for my improved sealing operation, and adapted for use with the tool, is indicated by the numeral 24. It comprises a crown portion 26 preferably rounded as indicated at 28 into a vertical side wall 30 and having an annular flange 32 with an angle piece 34 extending around the outer periphery thereof. The cap may be sheet metal and stamped in a single piece.

Plug 14 having been threaded into the bung ring, seal-cap 24 is dropped into the seat formed in the upper surface of the bung flange by recess 20. The seal-cap is so dimensioned that in performing this operation the outer periphery thereof just clears the upper tip of the 45° undercut indicated at 22. It is therefore apparent that the cap may be applied rapidly and easily, there being no need for centering or adjusting the same with reference to the bung assembly prior to locking the cap to the flange.

The angle piece 34 is then expanded radially outwardly into the undercut 22 of recess 20, thereby firmly locking the cap in the flange and precluding access to the drum by removal of the concealed plug without first removing the seal-cap. Such removal would be readily detected and thus the consignee of the drum contents would realize that the drum had been tampered with.

65 The tool for expanding the seal-cap into lock-

ing engagement with the bung flange is illustrated in Figs. 1-3. It comprises a housing 36 open at the base and having a skirt 38 externally threaded around the lower portion thereof to receive an internally threaded collar 40 which is provided with a lip 42 extending radially inwardly beyond the skirt 38. Four segmental expanding members 44 are positioned within the housing for radial movement therein. An endless coil spring 46 positioned within aligned grooves 48 in the outer walls of the expanding members tends constantly to contract them.

The inside face of each expanding member is tapered along spaced portions as indicated at 50 and 52, thereby forming in the aggregate an upper cone and a somewhat smaller lower cone for a purpose to be more clearly brought out hereinafter. Contraction of the expanding members 44 is limited to such movement as will bring the vertical faces 54 of the inside bottom wall portions of each segment into contact with one another. This movement is not sufficient to permit the said expanding members to drop through the supporting lip 42 which retains them in the housing.

A casing sleeve 56 is threaded into an annular groove 58 in the top of casing 36 and an apertured cap 60 is threaded as indicated at 62 onto the upper end of the said casing sleeve. Plunger 64 is slideable through the aperture in cap 60 and is provided with a reduced portion 66 adjacent its lower extremity adapted to slide through an opening in the top of housing 36. The shoulder 68 formed by the reduced lower portion of the plunger clears the top of casing 36 when the plunger is fully depressed. A slideable collar 70 is adjustably positioned with reference to plunger 64 as by means of set screw 72, which collar provides an upper seat for coil spring 74, the bottom of which seats on housing 36, thereby providing a constant force tending to urge the plunger to the upper limit of its movement. In the particular form illustrated the upper portion of the plunger is reduced in diameter to form a shoulder 76 which provides a stop for collar 78 slidably positioned on the upper reduced portion of the plunger and adjustable with reference thereto by means of set screw 80. A heavy cast iron ball 82 is slideable along the upper reduced portion of the plunger, its upper limit of movement being marked by collar 84 which is preferably slideable and adjustable with reference to the plunger.

The under side of housing 36 is provided with a recess 86 for seating the upper cylindrical portion 88 of a generally cone-shaped cam 90 integral with or secured to the bottom of the plunger, the taper of which corresponds to the taper of spaced cone seats 50 and 52 formed by the segmental expanding members. These cone seats are separated by a straight-walled portion 92 which forms a seat for the cylindrical wall portion 88 of the cam cone.

Each segmental expanding member 44 is provided with peripheral toe portions 94, the hypotenuse of each of which is somewhat rounded, as indicated in somewhat exaggerated form in Fig. 6 at 96, to facilitate the expanding action thereof in locking the seal-cap in the undercut of the bung flange.

In operation the seal-cap 24 is first dropped into recess 20 as indicated in Fig. 4. The weight of ball 82 overcomes the normal upward thrust of spring 74 to retain cam cone 90 in its lower seat when the tool is not in use, thus forcing the

expanding segments outwardly against the tension of coil spring 46 to prevent relative movement of the parts and consequent wear and tear. When seal-cap 24 is to be expanded into locking engagement, ball 82 is lifted to remove its weight and permit coil spring 74 acting on collar 70 to urge the plunger to its uppermost position, the limit of upward movement being reached when cam cone 90 seats in socket 86 provided therefor in casing 36. As cam cone 90 moves to its upper seat, spring 46 contracts the expanding members. When the tool is contracted the inside of toe portions 94 just clear the rounded crown 28 of the seal-cap, which is somewhat higher than angle portion 34 of the seal-cap flange. This rounded crown therefore functions as a guide to prevent the toes of the expanding segments from fouling the upper edge of angle piece 34 when the sealing tool is positioned. The toes 94 being seated on flange 32 of the seal-cap, the collar 78 is struck forcibly by sliding ball 82 downwardly. This forces the plunger downwardly and cam cone 90 operates against the tapered seat of lower cone 52 to expand the segments. During expansion the toes 94 force the upturned edge 34 of the seal-cap into the undercut 22 of the recess provided in the bung flange.

The tool is released by again lifting ball 82, thereby permitting the spring 74 to lift cam cone 90 into its upper seat which in turn permits spring 46 to contract the expanding segments.

The rounded hypotenuse 96 of toes 94 on the expanding segments tends to draw the vertical line of the seal-cap rim downwardly while the base flange 32 remains seated in the recess 20. The metal in seal-cap flange 32 and its rim or angle portion 34 is preferably sufficient to leave an inturned marginal rim portion 98 within the cleft provided by undercut 22, thus rendering unauthorized removal of the seal-cap still more difficult.

While in this application I have disclosed a preferred means for locking the seal-cap in the bung flange cleft, it will be apparent that various modified arrangements may be used to accomplish this. Likewise, a preferred form of seal-cap has been illustrated without intending to limit in any way the improved sealing operation disclosed herein.

Various modifications of the structure and means heretofore described will be apparent to those skilled in the art and for that reason I wish to limit myself only within the scope of the appended claims.

55. What I claim is:

1. A portable sealing tool for the purpose described including in combination a casing having an open bottom, expanding members so positioned therein as to permit limited free bodily movement of each in the same plane in a radial direction and including a peripheral lip portion extending below the casing, yieldable means normally urging said members to full contracted position, and movable means carried by said casing operable to positively engage said members to expand the same against said yieldable means, said means including a portion extending through said casing to the exterior thereof and a weight slidably mounted thereon for limited movement therealong.

2. A portable sealing tool for the purpose described including in combination a casing having an open bottom, expanding members so positioned therein as to permit limited free bodily movement of each in the same plane in a radial

direction and including a peripheral lip portion extending below the casing, yieldable means normally urging said members to full contracted position, movable means carried by said casing operable to positively engage said members to expand the same against said yieldable means, said means including a portion extending through said casing to the exterior thereof and a weight slidably mounted thereon for limited movement therealong, and yieldable means normally urging said movable means into inoperative position.

3. A portable sealing tool for the purpose described including in combination a casing having an open bottom, expanding members so positioned therein as to permit limited free bodily movement of each in the same plane in a radial direction and including a peripheral lip portion extending below the casing, yieldable means normally urging said members to full contracted position, movable means carried by said casing operable to positively engage said members to expand the same against said yieldable means, said means including a portion extending through said casing to the exterior thereof and a weight slidably mounted thereon for limited movement therealong, yieldable means normally urging said movable means into inoperative position, and manually operable means associated with said movable means for controlling the tension in said last-mentioned yieldable means.

4. A portable sealing tool for the purpose described including in combination a substantially cylindrical housing, expanding members so positioned therein as to permit limited free bodily movement of each in the same plane in a radial direction, yieldable means urging said members into full contracted position, means movable from inoperative position, permitting full contraction of the members, into engagement therewith to expand the same, said means including a portion extending through said casing to the exterior thereof and a weight slidably mounted thereon for limited movement therealong, yieldable means associated with said movable means constantly urging the same into inoperative position, and manually operable means associated with the movable means for varying at will the tension in said last-mentioned yieldable means.

5. A portable sealing tool for the purpose described including in combination a substantially cylindrical housing, expanding members so positioned therein as to permit limited free bodily movement of each in the same plane in a radial direction, said members including a peripheral toe portion extending outside said housing, yieldable means urging said members into full contracted position, means movable from inoperative position, permitting full contraction of the members, into engagement therewith to expand the same, said means including a portion extending through said casing to the exterior thereof and a weight slidably mounted thereon for limited movement therealong, yieldable means associated with said movable means constantly urging the same into inoperative position, and means associated with the movable means for varying at will the tension in said last-mentioned yieldable means.

6. A portable sealing tool for the purpose described including in combination a substantially cylindrical housing, expanding members so positioned therein as to permit limited free bodily movement of each in the same plane in a radial direction, said members including a peripheral toe portion extending outside said housing, said

toe portion including a peripheral lip having a flat under surface and rounded outer wall, yieldable means urging said members into full contracted position, means movable from inoperative position, permitting full contraction of the members, into engagement therewith to expand the same, said means including a portion extending through said casing to the exterior thereof and a weight slidably mounted thereon for limited movement therealong, yieldable means associated with said movable means constantly urging the same into inoperative position, and means associated with the movable means for varying at will the tension in said last-mentioned yieldable means.

7. A portable sealing tool for the purpose described including in combination a cylindrical casing having an open bottom, segmental expanding members floatingly contained therein for independent bodily movement in a radial direction, means for limiting such movement, each member including a peripheral lip portion extending through the bottom of said casing, yieldable means normally urging said members to full contracted position, and movable means carried by said casing and engageable with said members to force the same radially outwardly against the tension of said yieldable means, said means including a portion extending through said casing to the exterior thereof and a weight slidably mounted thereon for limited movement therealong.

8. A portable sealing tool for the purpose described including in combination a cylindrical casing having an open bottom, segmental expanding members floatingly contained therein for independent bodily movement in a radial direction, means for limiting such movement, each member including a peripheral lip portion extending through the bottom of said casing, each of said peripheral lips having a plane-surfaced bottom face and a rounded nose, said casing including means for limiting the outward movement of said members so that the nose of said peripheral lips does not extend beyond the cylindrical wall of the casing, yieldable means normally urging said members to full contracted position, and movable means carried by said casing and engageable with said members to force the same radially outwardly against the tension of said yieldable means, said means including a portion extending through said casing to the exterior thereof and a weight slidably mounted thereon for limited movement therealong.

9. A portable sealing tool for the purpose described comprising in combination a cylindrical housing open at one end, a collar threadedly received over the open end thereof and including a continuous lip extending radially inwardly to form an annular supporting ledge, segmental expanding members within said housing slidably seated upon said ledge and each including a peripheral lip extending through the open end of said housing, yieldable means engaging said segmental members and urging them toward one another, camming means within said housing for expanding said segmental members against the resistance of said yielding means, said camming means including a portion extending through said housing, a collar adjustably positioned on said extending portion, a coil spring seated between the outer face of said housing and said collar, and means for limiting the movement of said camming means and its extended portion.

10. A portable sealing tool for the purpose described comprising in combination a cylindrical housing open at one end and apertured at the other, expanding members supported within said housing for independent radial movement in the same plane, each expanding member including a peripheral lip extending through the open end of said housing, camming means within said housing cooperable with said expanding members to move the same radially outward, said camming means including a stem extending through the aperture in said housing, a sleeve secured to said housing and enveloping a portion of said stem, weight means slidable along the exposed portion of said stem, and means for varying the extent of permissible movement of said weight.

11. A portable sealing tool for the purpose described comprising in combination a cylindrical

housing open at one end and apertured at the other, a collar threadedly received over the open end thereof and including a continuous lip extending radially inwardly to form an annular supporting ledge, expanding members supported within said housing upon said ledge for independent radial movement in the same plane, each expanding member including a peripheral lip extending through the open end of said housing, camming means within said housing cooperable with said expanding members to move the same radially outward, said camming means including a stem extending through the aperture in said housing, a sleeve secured to said housing and enveloping a portion of said stem, weight means slidable along the exposed portion of said stem, and means for varying the extent of permissible movement of said weight.

JOHN R. PROCTOR.
